[57] **CLAIM**

The ornamental design for a bullnose saddle pliers, as shown and described.

DESCRIPTION

FIG. 1 is a perspective view taken from the top, front, and left side of the bullnose saddle pliers showing our new design;

FIG. 2 is a front elevational view thereof, the rear side being the same as the front;

FIG. 3 is a right side elevational view thereof, the left side being the same as the right side;

FIG. 4 is a top view thereof;

FIG. 5 is a bottom plan view thereof; and,

FIG. 6 is an alternate perspective view thereof taken from the top, front and left side, with the jaw in an open position and the handles shown fragmentarily for ease of illustration.

FIG. 1

FIG. 2

FIG. 3

FIG. 4

FIG. 5

FIG. 6
